(57) **CLAIM**

I claim the ornamental design for a stand for arm and leg exerciser, as shown and described.

DESCRIPTION

FIG. 1 is a top and right side perspective view of a stand for arm and leg exerciser, embodying our new design;

FIG. 2 is a right side elevation view thereof;

FIG. 3 is a left side elevation view thereof;

FIG. 4 is a front side elevation view thereof;

FIG. 5 is a back side elevation view thereof;

FIG. 6 is a top plan view thereof; and,

FIG. 7 is a bottom plan view thereof.

The broken lines shown are included for the purpose of illustrating the unclaimed portions of the article and form no part of the claim.

1 Claim, 7 Drawing Sheets
